UNITED STATES PATENT OFFICE.

DAVID W. R. MORGAN, OF SWARTHMORE, PENNSYLVANIA, ASSIGNOR TO WESTINGHOUSE ELECTRIC AND MANUFACTURING COMPANY, A CORPORATION OF PENNSYLVANIA.

SURFACE CONDENSER.

Application filed June 3, 1921, Serial No. 474,854. Renewed February 4, 1926.

To all whom it may concern:

Be it known that I, DAVID W. R. MORGAN, a citizen of the United States, and a resident of Swarthmore, in the county of Delaware and State of Pennsylvania, have invented a new and useful Improvement in Surface Condensers, of which the following is a specification.

My invention relates to surface condensers, and more particularly to horizontal tube condensers of the radial flow type, and it has for an object the provision of an apparatus of the character designated which shall be simple in construction and which shall deliver non-condensable gases to a withdrawal mechanism at a low temperature and specific volume. These and other objects, which will be made manifest throughout the description of my invention, may be attained by an apparatus illustrated in the accompanying drawing in which

Figure 1 is a longitudinal sectional view of a condenser embodying my invention taken on line 1—1 of Figure 2, the cooling tubes being omitted to show more clearly the air offtake apparatus; Figure 2 is a transverse sectional view thereof taken on line 2—2 of Figure 1; and Figure 3 is a transverse sectional view of a water box taken on line 3—3 of Figure 1.

In a radial flow condenser, as commonly constructed, a cylindrical nest of cooling tubes is arranged concentrically of and spaced from the longitudinally extending wall of the condenser shell in such a manner that steam, or other fluid to be condensed, may enter the tube nest at substantially any point in its perimeter. The flow of steam is radial through the tube nest and toward a centrally located off-take. Normally, the condensable portions of the steam are for the most part separated from the non-condensable gases upon reaching the off-take. The non-condensable gases, together with some uncondensed vapors, hereinafter termed air for brevity and convenience for description, are withdrawn through the centrally disposed off-take by means of an air pump of suitable construction. This type of condenser has a larger condensation capacity than condensers of equal size of the usual

construction, due to the large entrance area for the steam presented by the eccentrically arranged tube nest and the short path of travel through the cooling tubes.

It is the purpose of my present invention to improve the efficiency of this type of condenser by reducing the amount of energy required to withdraw the air from the condenser. This result is attained by providing means for reducing the specific volume of air being withdrawn prior to its delivery to the air pump. As illustrated, I provide a V-shaped chamber disposed in a lower central zone of the tube nest, and having an open top disposed well within the nest of tubes for admission of air from the tube nest. Some of the cooling tubes are embraced within the walls of the V-shaped chamber and serve to reduce the temperature and the specific volume of the air passing therethrough. The air passes downwardly through the chamber in a path of decreasing flow area and is discharged without the condenser in any suitable manner.

Referring to the drawings for a fuller understanding of my invention, I indicate a condenser at 10 having a shell 11, a steam inlet 12, and a condensate outlet means 13. A cylindrical nest of tubes 14 is so located within the shell that there is an adequate steam space 15 between the tubes and the longitudinally extending walls of the shell 11, which space communicates with the inlet 12 and almost entirely surrounds the nest of tubes.

As is customary in surface condenser construction, water boxes 16 are bolted or otherwise secured to the shell 11, tube plates 17 being held between the flanges on the water boxes and cooperating flanges of the shell. The tubes 14 are secured in the tube plates 17 and open into the water boxes 16 in the usual manner.

Within the lower portion of the tube nest, I provide a cooling chamber 18 of V-shaped cross-sectional conformation, the side walls 19, 20 of which extend the full length of the condenser shell and are preferably secured to the tube plates 17 by means of flanges 21. The open top 22 of the V-shaped cooling chamber is disposed well within the nest of

tubes for the purpose of securing a uniform flow of steam radially throughout the tube nest. A roof member 23 extends over and is spaced above the opening 22 and may preferably be secured to the tube plates 17 by means of flanges 24.

The air may be withdrawn from the V-shaped cooling chamber in any convenient manner. As illustrated, the walls 19, 20 of the chamber 18, converging toward their lower edges, are secured throughout their length to a conduit 25 in such a manner that an open communication is provided between the chamber 18 and the conduit 25. The conduit 25, as shown, extends outwardly through one of the water boxes 16 to a suitable air withdrawal mechanism (not shown). It will be understood that the construction of the conduit 25 and its specific relation to the chamber 18, above described, is merely illustrative and that the air, or non-condensable gases, may be removed from the chamber 18 in any suitable manner, as through the hot well or even through the bottom of the condenser.

Any suitable means may be provided for removing the liquid of condensation which may collect in the discharge conduit 25. In the drawing I have shown a manometric tube 26 which delivers the liquid collected in the conduit 25 into the hot well 13 of the condenser. The water of condensation accumulating in the hot well 13 is withdrawn in the usual manner through a port 27.

Having described the arrangement of an apparatus embodying my invention, the operation thereof is as follows: Steam from a turbine or other steam consumer, is admitted into the condenser through the inlet 12 and passes downwardly within the shell in such a manner as to substantially surround the nest of cooling tubes. The cylindrical entrance area to the tube nest enables the condenser to handle large volumes of steam, and the steam passes radially through the nest of tubes toward the open top 22 of the off-take chamber 18 which is disposed in a substantially central position within the tube nest. During the passage of the steam through the cooling tubes, the condensable portions thereof are almost entirely converted into liquid so that the non-condensable portions having a small condensable fluid content enter the chamber 18 and pass downwardly therethrough over the cooling tubes. During the passage downwardly through the chamber 18, the condensable content of the air is further separated out and the temperature and volume of the air materially reduced. The decrease in flow area presented by the converging walls of the chamber 18 corresponds substantially to the decrease in volume of the air passing therethrough and thus facilitates the withdrawal of the air. The roof member 23

shields the open end 22 of the chamber 18 and prevents the condensate raining down from the cooling tubes above from entering the chamber.

The air at a lower temperature and specific volume is discharged through the bottom of the chamber 18 into the conduit 25 by which it is carried without the condenser through the water box 16, where its temperature and specific volume are further reduced, due to the contact of the cooling water with the conduit 25, and thence delivered to a suitable air pump. The water of condensation forming upon the tubes 14 within the chamber 18 drains into the conduit 25 and is conducted therefrom by means of the manometric tube 26 into the hot well 13. The condensate within the hot well 13 is removed through the port 27 by a suitable condensate pump as will be understood by those skilled in the art.

While I have shown my invention in but one form, it will be obvious to those skilled in the art that it is not so limited, but is susceptible of various other changes and modifications without departing from the spirit thereof, and I desire, therefore, that only such limitations shall be placed thereupon as are imposed by the prior art or as are specifically set forth in the appended claims.

What I claim is:

1. In a condenser, a shell having a steam inlet means and condensate outlet means, a nest of tubes within the shell, a triangular section of said tubes partitioned from the remainder of the tubes, inlet means at a side of the triangular section so disposed as to receive fluids which have traversed the said remainder of the tubes and an outlet means at the vertex of said triangular section opposite to said side, whereby the fluids traversing the triangular section of tubes travel in a path of decreasing flow area transverse to the tubes of the triangular section.

2. In a condenser, a shell having a steam inlet means and condensate outlet means, a nest of tubes within the shell, a V-shaped partition means embracing a triangular section of said tubes, inlet means for the triangular section of tubes at the open end of the V-shaped partition and so disposed as to receive fluids which have traversed the tubes not embraced by said partition, and an outlet means at the vertex of the triangular section of tubes opposite to the inlet means, whereby the fluids traversing the triangular section of tubes travel in a path of decreasing flow area transverse to the tubes of the triangular section.

3. In a condenser, a shell having a steam inlet means and condensate outlet means, a nest of tubes within the shell, a V-shaped partition means embracing a triangular sec-

tion of said tubes and having the open end of the V disposed within the nest of tubes to serve as an inlet for fluids which have traversed the tubes not embraced by said partition, a baffle disposed above said open end, and an outlet means at the vertex of the triangular section of tubes opposite to the inlet means, whereby the fluids traversing the triangular section of tubes travel in a path of decreasing flow area transverse to the tubes of the triangular section.

4. In a condenser, the combination with a shell having inlet means, condensate outlet means and a nest of cooling tubes located within the shell and spaced therefrom so that steam may enter substantially any portion of the perimeter of the tube nest, of a non-condensable-gas off-take chamber extending the length of the shell and having an open top located well within the tube nest, a portion of the cooling tubes traversing said off-take chamber, and a longitudinally extending conduit forming the bottom of the off-take chamber and extending outwardly of the condenser.

5. In a condenser, the combination with a shell having steam inlet means, condensate outlet means, a nest of cooling tubes located within the shell and spaced therefrom, so that steam may enter substantially any portion of the perimeter of the tube nest, and water boxes at each end of the shell, of a non-condensable-gas off-take chamber extending the length of the shell and having an open top located well within the tube nest, a portion of the cooling tubes traversing said off-take chamber, and a longitudinally extending conduit forming the bottom of the off-take chamber and extending outwardly through a water box of the condenser.

6. In a condenser, the combination with a shell having a nest of cooling tubes therein spaced away from the shell to form a steam delivery space substantially surrounding the tube nest, of a non-condensable-gas off-take chamber extending into said tube nest and comprising a V-shaped chamber embracing a portion of the cooling tubes, the open top of the V-shaped chamber being adjacent a central portion of the tube nest, and means associated with the closed edge of the V-shaped chamber for withdrawing the non-condensable gases from the condenser.

55 7. In a condenser, the combination with a shell having a nest of cooling tubes therein spaced away from the shell to form a steam delivery space substantially surrounding the tube nest, of a non-condensable-gas off-take chamber extending into said tube nest and comprising a V-shaped chamber embracing a portion of the cooling tubes, the open top of the V-shaped chamber being adjacent a central portion of the tube nest, a roof member above the open top of the V-shaped cham-

ber and means associated with the closed edge of the V-shaped chamber for withdrawing the non-condensable gases from the condenser.

8. In a condenser, the combination with a shell having a nest of cooling tubes therein spaced away from the shell to form a steam delivery space substantially surrounding the tube nest, of a non-condensable-gas off-take chamber extending the length of the shell and having an open top located well within the tube nest and comprising a V-shaped chamber embracing a portion of the cooling tubes, and means associated with a portion of said off-take chamber remote from said open top for withdrawing non-condensable gases from the condenser.

9. In a condenser, the combination with a shell having a nest of cooling tubes therein spaced away from the shell to form a steam delivery space substantially surrounding the tube nest and water boxes at each end of the shell, of a non-condensable-gas off-take chamber extending into said tube nest and comprising a V-shaped chamber embracing a portion of the cooling tubes, the open top of the V-shaped chamber being adjacent a central portion of the tube nest, and a longitudinally extending conduit forming the bottom of the off-take chamber and extending outwardly through a water box of the condenser.

10. In a condenser, the combination with a shell defining a condensing chamber and a nest of cooling tubes traversing said chamber, of a V-shaped non-condensable-gas off-take chamber in the lower central portion of the tube nest and having its open top well within the tube nest, a portion of the cooling tubes traversing the off-take chamber, and means associated with a portion of said off-take chamber remote from said open top for withdrawing non-condensable gases from the condenser.

11. In a condenser, the combination with a shell defining a condensing chamber and a nest of cooling tubes traversing said chamber, of a V-shaped non-condensable-gas off-take chamber in the lower central portion of the tube nest and having its open top well within the tube nest, a portion of said cooling tubes traversing the off-take chamber, a roof member above the open top of the V-shaped chamber and means associated with the closed edges of the V-shaped chamber for withdrawing the non-condensable gases from the condenser.

12. In a condenser, the combination with a shell defining a condensing chamber, a nest of cooling tubes traversing said chamber and water boxes at each end of the shell, of a V-shaped non-condensable-gas off-take chamber in the lower central portion of the tube nest and having its open top well within the tube nest, a portion of said cooling tubes

traversing the off-take chamber, and a longitudinally extending conduit forming the bottom of the off-take chamber and extending outwardly through a water box of the condenser.

13. In a condenser, the combination with a shell and tube plates defining a condensing chamber, a nest of cooling tubes secured in the tube plates and traversing said chamber, and water boxes associated with each tube sheet, of an air off-take chamber within the nest of tubes, a portion of the tubes traversing the off-take chamber, and an offtake conduit leading from said off-take chamber and passing outwardly through a tube sheet and its associated water box, whereby the temperature and specific volume of the air being withdrawn are reduced.
14. In a condenser, the combination with a shell and tube plates defining a condensing chamber, a nest of cooling tubes secured in the tube plates and traversing said chamber, and water boxes associated with each tube sheet, of an air off-take chamber within the nest of tubes, a portion of the tubes traversing the offtake chamber and an off-take conduit leading from said off-take chamber and passing outwardly through a tube sheet and its associated water box in such a manner that the portion of the conduit within the water box is entirely surrounded by water, whereby the temperature and specific

volume of the air being withdrawn is reduced.

15. In a condenser, the combination with a shell, a nest of cooling tubes within the shell and a water box at each end of the shell, of an air off-take chamber within the shell, means for reducing the temperature and specific volume of the air passing through the offtake chamber, and outlet means for said off-take chamber so disposed with respect to one of the water boxes that the air passing through the outlet means is further reduced in temperature and specific volume.

16. In a condenser, the combination with a shell, a nest of cooling tubes within the shell and a water box at each end of the shell, of an air off-take chamber within the shell, means for reducing the temperature and specific volume of the air passing through the offtake chamber and an off-take conduit extending from said off-take chamber and traversing one of said water boxes, whereby the cooling water within the water box further serves to reduce the temperature and specific volume of the air being withdrawn.

In testimony whereof, I have hereunto subscribed my name this 27th day of May, 1921.

D. W. R. MORGAN.
